UNITED STATES PATENT OFFICE.

BERNARD HAUSMANN, OF SAN FRANCISCO, CALIFORNIA.

SLIDABLE AND SWINGING WINDOW-SASH.

SPECIFICATION forming part of Letters Patent No. 635,437, dated October 24, 1899.

Application filed June 22, 1899. Serial No. 721,472. (No model.)

To all whom it may concern:

Be it known that I, BERNARD HAUSMANN, a citizen of the United States, residing in the city and county of San Francisco, State of California, have invented an Improvement in Slidable and Swinging Window-Sashes; and I hereby declare the following to be a full, clear, and exact description of the same.

My invention relates to a mechanism for sliding window-sashes and a means for disengaging such sashes, so that they are turnable about hinges to swing inwardly for the purpose of obtaining access to the outside of the sash.

15 It consists of the parts and the constructions and combinations of parts which I will hereinafter describe and claim.

Figure 1 is a horizontal section of the window, showing the lower or inner sash partly 20 opened about its hinges and the upper or outer one closed; also, the construction of parting-strip between both sashes, the grooves in inside and outside stops, and the slides. Fig. 2 is a perspective view of the hinged side, 25 showing the construction and application of combined hinge-slide and locking device. Fig. 3 is a perspective view of the counterweight-slide upon the opposite side and the means for locking it when the sash is to be 30 disengaged therefrom. Fig. 4 is a partial section showing the hook L and its stop.

A A are pulley-stiles.

B B' are the upper and lower sashes, respectively, one edge of each sash being hinged 35 at one side, as will be hereinafter described, and the opposite edge closing against slides C, with which the counterweight-cord is connected, so that when the detachable edge of the sash is interlocked with the slide the 40 counterweight acts to balance a portion of the weight of the sash.

To swing the sash inwardly, it is necessary to lock the slide C to permit the detachment of the sash and to prevent the counterweight 45 from drawing it to the top of the window after the sash has been disengaged therefrom. In order to lock the slide before the sash is disengaged from it, I have shown a plate D or like device fixed flush with the pulley-stile 50 a short distance above the middle of the window-frame, having holes d made through it, as shown plainly in Fig. 3.

E is a stop and key having projections e, adapted to enter the holes d. When the slide C has been drawn so as to expose these 55 holes, the projections e are pushed into the holes, the head E projecting above the upper end of the slide C, so that when the window is raised the slide C is arrested at that point. By the momentum of lifting to the point of 60 contact with the stop E the slide C is arrested and the sash is disengaged and unlocked from same and can be swung inwardly about its hinges.

The hinges are made, as plainly shown in 65 Fig. 1, so that the joint F, about which the sash is turnable, stands outside the line of the window-stops G for the purpose of allowing the sash to swing clear of the stop and casing when opened. From this hinge-joint 70 F the part H extends to and forms a part of the slide I, which is, as shown, of metal of about the same thickness as the part H of the hinge and is slideable in grooves or channels J, made, respectively, in the outer stop and 75 inner stop of the window-frame and on one side of the parting-strip K. The other hinge-plate H' curves from the pivot-pin F over the part H, then extends parallel with it, thence being bent at right angles across the inner 80 edge of the sash, as shown at H², and is secured to this edge of the sash by screws or other fastenings.

All the hinge and slide attachments except 85 one in the lower sash are of the same construction. The one which differs is the lower hinge of the lower sash. Opposite this hinge I have shown a mortise made in the edge of the sash to receive the locking-hook L, and in this construction the part H' of the hinge 90 extends straight across the bottom of the mortise from the hinge-joint F instead of being bent parallel with the part H, as shown in the other hinges. This mortise forms a chamber for the locking-hook L to turn into. 95

When unlatched from the slide C, the sash is retained in place partly by the counterweight acting upon it on the hinged side and by the parting-strip and grooves in the inside and outside stops, which hold the sliding plate 100 attached to the hinge and prevent its falling out.

The sash is held above the window-sill, when opened, by means of a fulcrumed hook

L, which is so pivoted to the sliding plate that the upper end will drop by gravitation. This hook L is fulcrumed to the slide I, as shown, and when the sash is opened the upper 5 part of this hook falls over against the channel or recess P in the pulley-stile and slides down with the movement of the sash until it reaches the stopping-plate, which arrests and holds the sash above the window-sill.

10 The parting-strip K is made with a groove or channel J along the outer side to receive the sliding plate I of the upper sash, and on the opposite or inner side it is formed with a lug or projection K', which forms a similar 15 channel for the outer edge of the sliding plate I of the lower sash. The inner edge of this plate extends beyond the part H of the hinge-plate and slides in a similar groove or channel J', made beneath the inner stop G.

20 When the sash is in its normal position, it is closed and latched against the slide C in any usual or suitable manner, and thus engaged the sash and its counterweighted slide move up and down in unison in the usual 25 manner of such windows. In this condition the hook L is held in a vertical position and cannot engage the stop P or interfere with the sliding of the sash. When the sash is to be opened, it is down or is to be first drawn down 30 to expose the holes d above the slide C, and the key E is inserted above the slide C. The sash is then slightly raised, and when the slide C comes in contact with the key E any further slight lifting of the sash disengages 35 its detachable edge from the slide and allows the sash to be opened about its hinges. By reason of the hinge-joint F being set out as shown the sash immediately clears the casing and stops, and as it swings it releases the lug 40 L', so that the hook L drops by gravitation into the channel P, moving down until it is arrested by plate or shoulder at the bottom, so that the sash then hangs just above the window-seat and is freely turnable about its 45 hinges and can be opened inwardly. To open the upper sash, it is lowered to the sill and operated in like manner. By this construction it is necessary to cut away the sides of the window-sash and to insert slides of considerable thickness, which slides must project beyond the stops and parting-strip in order to allow the usual opening. It is only necessary to cut away mortise in the sash sufficient to receive the hook L and the lugs 55 in which it is journaled, while the plates I, being of comparatively thin metal, are screwed upon the edges of the sash, occupying but little space, and the grooves or channels J J', in which they slide, are equally narrow and 60 easily formed without mutilation of the sash. The stop or key upon the opposite side being independent can only be used by the one having possession of it, and undesirable interference with the window is thus prevented.

The parts are also much less expensive, and 65 the time necessary for fitting up a window with this device is very much lessened.

Having thus described my invention, what I claim as new, and desire to secure by Letters Patent, is—

70 1. In a hinged sliding window, the metal plates fixed to the edges of the sashes, projecting upon each side, stops and parting-strips having grooves or channels and tongues in which said edges are adapted to slide, and 75 hinge-plates projecting at right angles with said slides with the pivot-point exterior to the stops and parting-strips.

2. A hinged and slidable window having metal strips fixed to the inner edges of the 80 sashes and projecting upon each side, slots formed in the stops and parting-strips, in which the projecting edges of said slides are guided and movable, one hinge-leaf projecting at right angles from the slide to a point 85 beyond the line of the stops and parting-strips, the other leaf hinged thereto and fixed to the edge of the sash.

3. A hinged and sliding window having the combined sliding plates and hinges as shown, 90 and a locking-hook pivoted with relation to the sash with the upper end adapted to tilt by gravitation and to engage a stop in the pulley-stile when the sash is open about its 95 hinges, and a projecting lug to contact with the sash when it is closed, whereby the hook is thrown out of engagement with the stop and held in a vertical position in its chamber.

4. A combined hinge and slide for hinged 100 sliding windows consisting of a plate having the edges projecting beyond the edges of the sash and slidable in slots or channels formed in the stops and parting-strip, and a projection at right angles with said plate having the hinge-joint beyond the line of the stops and 105 parting-strip, and a similar plate fixed to the edge of the sash and pivoted to the projection of the sliding plate.

5. A hinged sliding window-sash, consisting of a sliding plate movable in guides in the 110 window-easing, having a projection at right angles, a second plate hinged to the projection beyond the line of the stops and parting-strip, and secured to the edge of the sash, a mortise formed in the edge of the sash, lugs 115 or plates turned at right angles with the sliding plate into the chamber of the sash, a hook pivoted between said lugs having its upper end adapted to tilt by gravitation so as to engage a stop in the pulley-stile, and a lug 120 projecting from the hook-plate which by the closing of the sash disengages the hook.

In witness whereof I have hereunto set my hand.

BERNARD HAUSMANN.

Witnesses:

S. H. NOURSE,
H. F. ASCHECK.

It is hereby certified that in Letters Patent No. 635,437, granted October 24, 1899, upon the application of **Bernard Hausmann**, of San Francisco, California, for an improvement in "Slidable and Swinging Window-Sashes," an error appears in the printed specification requiring correction, as follows: In line 48, page 2, after the word "is" the word *not* should be inserted; and that the said Letters Patent should be read with this correction therein that the same may conform to the record of the case in the Patent Office.

Signed, countersigned, and sealed this 14th day of November, A. D., 1899.

[SEAL.]

WEBSTER DAVIS,
Assistant Secretary of the Interior.
